S. W. RUGGLES.
CHEESE PRESS.

No. 11,241.

PATENTED JULY 4, 1854.

Fig. 2.

Fig. 1.

UNITED STATES PATENT OFFICE.

SOLOMON W. RUGGLES, OF FITCHBURG, MASSACHUSETTS, ASSIGNOR TO RUGGLES,
SMITH & AUSTIN.

SELF-ACTING CHEESE-PRESS.

Specification of Letters Patent No. 11,241, dated July 4, 1854.

To all whom it may concern:

Be it known that I, SOLOMON W. RUGGLES, of Fitchburg, in the county of Worcester and State of Massachusetts, have invented a new and useful or Improved Cheese-Press; and I do hereby declare that the same is fully described and represented in the following specification and the accompanying drawings, letters, figures, and references 10 thereof.

Of the said drawings, Figure 1, represents a front view of the said improved press. Fig. 2, is a central, vertical, and transverse section of it.

15 In the construction of said press, I employ a stationary upright supporting frame A, within which I make to freely slide upward and downward a rectangular frame B. The table or bed, C, upon which the cheese is 20 laid when pressed, is supported on the lower girt, *a*, of the frame, B, while the platen or follower, D, is made to slide freely upward and downward between said bed and the upper girt, *b*, of the frame B. To the upper 25 side of said platen and near to its ends I respectively hinge two upright struts, *c*, each of which at its upper end carries a friction roller *c'*, which rests and bears against the underside of the upper girt of the movable frame, B, as seen in the drawings. 30 The said frame, B, plays between the two upper girts, *d*, *e*, of the frame, A, and there is hinged or jointed to each one of these girts and one of the struts, a connecting rod 35 or bar or rod, *e'*, *f'*, as seen in the drawings.

Between the two upper girts of the stationary frame and at or near the middle of the same, there is a windlass, H, whose 40 shaft extends through and is supported in the girts and has a crank, I, fixed on one end of it. A cord, K, from the windlass barrel is fastened to the platen so that when such windlass is turned in one direction so 45 as to wind up the cord, the platen shall be lifted. This lifting of the platen will of course lift the struts so as to cause the frame, B, to be forced or lifted upward. At the same time by the operation of the 50 connecting rods of the struts in passing from near a horizontal to nearly a vertical

position, the upper ends of the struts will be drawn inward and so as to produce an elevation of the platen with respect to the bed. If under such circumstances, or when 55 the frame, B, is elevated to its highest position we place a cheese upon the bed and suffer the frame, B, and cheese to fall downward together, the action of the frame, B, on the struts and connecting rods, will be 60 such as to cause the struts to depart from one another and take vertical positions and press the platen downward toward the bed and upon the cheese.

This is a self pressing cheese press. It 65 is termed self pressing because the power applied to effect the pressure is that of the combined weight of the cheese, the bed, the platen, the frame, B, and the struts, *c*.

I am aware that cheese presses, wherein 70 the power applied to effect the pressure is the weight of the cheese, the movable frame, and apparatus connected therewith, have been before invented and patented; one such having been patented in December, A. D. 75 1831, by one Crane or Crain of Hanover, in the State of New Hampshire, while another such was patented by Bethuel Gillett and Lyman Allis August 26, 1851. I do not claim either of the devices as patented or 80 described by such persons in their specifications. My invention being an improvement on the self acting cheese-press, which has an inner movable frame, a movable platen, and a system of levers or toggle joints. 85 Nor do I claim an arrangement of pressure levers as exhibited in the cheese press patented on the 15th day of August, A. D. 1837, by Sullivan White, such levers not only having their fulcra supported by the top 90 girts of the movable frame and their inferior arms working against the platen or follower, but their superior arms resting and sliding against pins or rollers applied to the stationary frame; the said arrangement being not only cumbersome, but attended with much friction in its operation, but 95

What I do claim is—

The general construction and application 100 of the pressing power or mechanism as described or the arrangement of the pressure

bars or struts, *c*, *c*, and the arms or pitmen, *e'*, *f'*, and their application to the remaining stationary and movable parts of the press as specified, whereby the press is made to operate in manner as explained and to great advantage and power, and with little friction, and is reduced to a very desirable and compact form.

In testimony whereof, I have hereunto set my signature this tenth day of January, 10 A. D. 1854.

SOLOMON W. RUGGLES.

Witnesses:

DAVID H. MERRIAM,
DUNCAN CHISHOLM.
